(57) **CLAIM**

The ornamental design for a chair desk combination frame, as shown and described.

DESCRIPTION

FIG. 1 is a perspective view of a chair desk combination frame showing my new design;

FIG. 2 is a front elevation view thereof;

FIG. 3 is a left side view thereof;

FIG. 4 is a right side view thereof;

FIG. 5 is a top view thereof;

FIG. 6 is a bottom view thereof; and,

FIG. 7 is a back elevation view thereof.

The broken lines in the drawings are for illustrative purposes only and form no part of the claimed design.
